BRUSH HOLDER

Filed June 10, 1946

INVENTOR.
Charles Howard Pierce

BY *O. W. A. L. and*

ATTORNEY.

UNITED STATES PATENT OFFICE

2,450,736

BRUSH HOLDER

Charles Howard Pierce, Kalamazoo, Mich.

Application June 10, 1946, Serial No. 675,701

9 Claims. (Cl. 248—112)

1

The main objects of this invention are:

First, to provide a brush holder for paint brushes and the like with which the brush may be quickly engaged and disengaged and at the same time one which is effective in supporting the brush.

Second, to provide a brush holder which may be supported from the rim of a container and comprising a jaw member which may be vertically adjusted to accommodate brushes of different sizes and to permit the brush being submerged, for example in a cleaning liquid or liquid designed to prevent hardening of the paint on the brush.

Third, to provide a structure having these advantages which may be engaged with a support other than a container for the storage or supporting of brushes not in use.

Objects relating to details and economies of the invention will appear from the description to follow. The invention is defined and pointed out in the claims.

Preferred embodiments of the invention are illustrated in the accompanying drawing, in which:

Fig. 1 is a perspective view of a brush holder embodying my invention in operative relation to a container indicated by dotted lines.

Fig. 2 is an enlarged view in section on a line corresponding to line 2—2 of Fig. 1.

Fig. 3 is an enlarged fragmentary view in vertical section on a line corresponding to line 3—3 of Fig. 2, the jaw member being shown in one position of adjustment by full lines and in another by dotted lines.

Fig. 4 is a fragmentary side elevation of a modified form or embodiment of the invention, the modification being in the brush engaging jaws.

Fig. 5 is a front elevation of the structure shown in Fig. 4.

Fig. 6 is a fragmentary perspective view of still another form or embodiment of the invention.

In the embodiment of the invention illustrated, the suspending hook or hanger designated generally by the numeral 1 is formed of a length of wire folded upon itself and bent to provide a downwardly facing hook 2 and depending hanger arms 3, 3. The lower ends of the arms are turned outwardly at 4 to engage the wall of the container and therefore support the hanger arms 3 in spaced relation to the wall of the container. The arms 3 are springable.

The jaw member designated generally by the numeral 5 is formed of a length of wire folded

2

and conformed to provide an upper loop 6 receiving the hanger arms 3. The arms 7, 7 of the loop extend downwardly and terminate in individual lower loops 8, 8 which engage within the hanger arms. The outer arms 9, 9 of these lower loops are extended upwardly and thence forwardly at 10 and thence inwardly at 11 providing a coacting pair of springable jaws adapted to receive the handle of a brush which may be presented laterally thereto—that is, pressed laterally between the jaws.

In the embodiment shown in Figs. 4 and 5, the upwardly extending arms 12 corresponding to the arms 9 have laterally turned upper ends 13 arranged in crossed relation and terminating in forwardly projecting jaws 14.

In the embodiment shown in Fig. 6, the arms 15 corresponding to the arms 9 and 12 of Figs. 1 to 3 and Figs. 4 and 5 diverge outwardly and have inwardly projecting portions 16 at their upper ends terminating in forwardly directed jaws 17.

In all of these embodiments, the brush may be easily engaged and disengaged with the jaws and at the same time is securely supported. The jaw member is clutchingly engaged with the hanger so that it may be vertically adjusted to the desired position.

It is desirable for a painter, for example, having a number of brushes to provide a holder for each brush. The holders may be mounted on the container where desired or on a support or engaged over a nail on the wall thus suspending the brush and preventing its bristles being distorted.

I have illustrated and described my invention in highly practical embodiments thereof. I have not attempted to illustrate or describe certain embodiments or adaptations which I contemplate as it is believed that this disclosure will enable those skilled in the art to embody or adapt my invention as may be desired.

Having thus described my invention, what I claim as new and desire to secure by Letters 45 Patent, is:

1. A holder for brushes and the like comprising a suspending hook having laterally spaced depending springable arms, and a jaw member formed to provide an upper loop and laterally spaced lower loops, the jaw member being extended upwardly and thence forwardly to provide a coacting pair of springable jaws, the straight reaches of both springable arms of said suspending hook being disposed through said upper loop, said arms being disposed individually in

the lower loops, said arms springably and frictionally engaging the edges of said loops and coacting to provide adjustable clutch engagement with the jaw member.

2. A holder for brushes and the like comprising a suspending hook having laterally spaced depending springable arms with straight center reaches, and a jaw member formed to provide a single loop and a laterally spaced pair of loops spaced vertically from said single loop, said jaw member being extended upwardly and thence forwardly to provide a coacting pair of springable jaws, the straight reaches of both springable arms of said suspending hook being disposed through said single loop, said arms being disposed individually in said pair of loops, said arms springably and frictionally engaging the edges of said loops and coacting to provide adjustable clutch engagement with the jaw member.

3. A holder for brushes and the like comprising a suspending hook having laterally spaced depending springable arms with straight center reaches having out-turned lower ends adapted to engage the inner side of a container when the hook is engaged over the rim thereof, and a jaw member formed of a length of wire folded to provide an upper loop and depending arms terminating in lower loops, the outer arms of the lower loops being extended upwardly and terminating in a coacting pair of springable jaws, the springable arms of said suspending hook being disposed through said upper loop, the lower loops being disposed between said arms, said loops springably and frictionally engaging said arms and coacting to provide adjustable clutch engagement with the arms.

4. A holder for brushes and the like comprising a suspending hook having laterally spaced depending springable arms, and a jaw member formed of a length of wire folded to provide an upper loop and depending arms terminating in lower loops, the outer arms of the lower loops being extended upwardly and terminating in a coacting pair of springable jaws, the springable arms of said suspending hook being disposed through said upper loop, the lower loops being disposed between said arms, said loops springably and frictionally engaging said arms and coacting to provide adjustable clutch engagement with the arms.

5. A holder for paint brushes and the like comprising a hanger, and a jaw member formed integrally of a length of wire folded to provide an

upper hanger engaging loop and depending arms terminating in lower hanger engaging loops, the outer arms of the lower loops being extended forwardly and terminating in coacting jaws, said loops springably and frictionally engaging said hanger and coacting to provide adjustable clutch engagement therewith.

6. A holder for brushes and the like comprising a hanger, and a jaw member formed of a length of wire folded and conformed to provide a hanger embracing loop with arms terminating in individual springable hanger engaging members, said wire extended from said individual hanger engaging members to provide springable arms, the arms terminating in brush receiving jaws.

7. A brush holder comprising a hanger having a suspending hook adapted to engage the rim of a container and a jaw member formed of a length of wire folded and bent to provide an upper loop receiving the hanger and depending arms terminating in lower loops springably engaging the hanger, the outer arms of the lower loops being extended upwardly and terminating in coacting brush engaging jaws.

8. A holder for brushes and the like comprising a hanger having depending laterally spaced springable arms, and a jaw member formed of wire folded and conformed to provide a loop disposed around said arms and with the ends of said wire extending between said arms and forming brush receiving jaws on the opposite side of said arms from the closed end of said loop.

9. A holder for brushes and the like comprising a hanger having depending laterally spaced arms, and a jaw member formed of wire folded and conformed to provide a loop disposed around said arms and with the ends of said wire extending between said arms and having portions overlapping said arms on the same side thereof as the closed end of said loop and being further extended to form brush engaging jaws.

CHARLES HOWARD PIERCE.
